Application August 19, 1940, Serial No. 353,166

2 Claims. (Cl. 122—169)

This invention relates to steam boilers, and more particularly to small automatically controlled boilers for supplying steam to heat the cabins in airplanes and the like.

An object of the invention is to provide a small, efficient boiler construction of extremely high capacity for its size and weight.

Another object is to provide a boiler that can be manufactured and maintained at low cost.

Other more specific objects and features of the invention will appear from the detailed description to follow, of a specific embodiment of the invention as disclosed in the drawings.

Briefly, a boiler in accordance with the invention consists of a water tube boiler of special design for high capacity, efficiency, and economy in construction and maintenance.

As previously indicated, the system is particularly useful as a source of auxiliary heat for aircraft where reliable automatic operation and safety against gasoline leaks are of paramount importance.

In the drawings:

Fig. 1 is a plan view of a twin unit boiler in accordance with the invention;

Fig. 2 is a front elevation of the boiler shown in Fig. 1;

Fig. 3 is a vertical sectional view through one of the units of the boiler, the section being taken substantially in the plane III—III of Fig. 1;

Fig. 4 is a plan view with portions broken away of one of the units of the boiler, the outer casing shown in Fig. 1 being removed;

Fig. 5 is a detail elevation view of a portion of the inner unit, the view being taken substantially along the line V—V of Fig. 4;

Fig. 6 is a detail elevational view taken substantially in the plane VI—VI of Fig. 3;

Fig. 7 is a detail section taken in the plane VII—VII of Fig. 4;

Fig. 8 is a detail section taken in the plane VIII—VIII of Fig. 6;

Fig. 9 is a schematic circuit diagram of a safety control circuit that may be employed with the boiler.

As shown in Figs. 1 and 2, the boiler of the present invention consists of two substantially identical boiler units mounted side by side in a common outer casing, the construction of each individual boiler unit being best shown in Figs. 3, 4, 5, 6, 7 and 8, inclusive. Thus each boiler comprises an inner shell 1 and an outer shell 2 interconnected at the top and bottom and defining an annular water and steam chamber. The inner and outer shells 1 and 2 are spaced rela-

tively close together for about two-thirds their height but at its upper end the inner shell 1 is drawn inwardly to a neck 3, whereas the outer shell 2 is cylindrical throughout its height. This provides a larger steam and water space at the upper end than at the lower end. The lower cylindrical portion of the inner shell 1 has a helical ridge or corrugation 4 projecting outwardly from the main portion of the wall and loosely contacting the outer shell 2. The outer face of the corrugation 4 is preferably welded to the outer shell 2 at frequent intervals to strengthen the inner shell against collapse under high steam pressure. The helical corrugation 4 defines a helical path 5 between the inner and outer shells through which water tends to circulate downwardly. However, it is desirable, in order to reduce the frictional resistance to water flow, to provide vertical indentations 6 (Figs. 6 and 8) in the corrugation 4 at frequent intervals to permit direct vertical movement of a portion of the water so that all of the water does not have to follow the tortuous helical path 5 in order to move from the upper end of the annular chamber to the lower end.

An annular top wall 7 interconnects the upper edge of the neck 3 and the outer shell 2, respectively. This end wall 7 also has a pair of nipples 8 and 9, respectively, extending therefrom to complete water and steam connections to the boiler, as will be described later.

The inner shell 1 defines a flue passage 10 for hot gases from a burner positioned immediately below the shell, and this flue is traversed by a large number of water tubes 11, each of which is connected at its lower and upper ends to the water and steam space. Thus at its lower end each of the tubes 11 (of which there are four as shown in Fig. 4), is welded to a nipple or sleeve 12 which extends through the inner shell 1 and is welded thereto. Likewise each of these water tubes 11 is connected at its upper end to a sleeve 12 which extends through the neck 3.

Each of the sleeves 12 is secured to the inner shell 1 before its insertion into the outer shell 2. This permits welding the sleeve 12 to the shell 1 on the outer surface of the latter, which is readily accessible prior to the assembly of the inner and outer shells. The water tubes 11 are assembled within the shell 1 after the sleeves 12 have been welded in place. The use of the sleeves 12 greatly facilitates the construction, since it is easier to weld the tubes 11 to the sleeves 12 than it would be to weld the ends of the tubes 11 directly to the shell 1. This also facilitates replacement of wa-

ter tubes, should they be damaged in service. In operation, the water tubes 11 become very highly heated by the gases moving upwardly through the flue 10, and the water within the tubes is rapidly converted into steam. This steam discharges from the upper ends of the tubes into the relatively large annular space 14 surrounding the neck 3. At the same time water circulates by gravity down through the helical passage 5 and through the recesses 6 to the lower end of the boiler, and thence into the lower ends of the tubes 11, where such water is again flashed into steam.

The outer shell 2 of each boiler unit is surrounded by a cylindrical shell 15 which is spaced from the shell 2 to define an annular space thereabouts. A top closure member 16 is formed with the shell 15. The gases from the burner, after passing through the flue 10, circulate down around the shell 2 in the annular space defined between the shell 2 and the shell 15, and escapes through a window 17, near the bottom of the latter, into a common vent passage 18 which carries away the products of combustion from both boiler units. Thus this passage 18 is defined in part by the shells 15 of the two boiler units (Figs. 1 and 2) and in part by rear and front walls 19 and 20, respectively. A nipple 21 at the upper end of the walls 19 is provided to complete connection to a stack 22, which can be extended to any desired point of discharge.

The gases from the burner are initially at a very high temperature but lose a great deal of their heat content to the water tubes 11 during their passage through the flue 10. Thereafter, during the passage through the annular space between the boiler shell 2 and the surrounding wall 15, they lose further heat to the water circulating through the helical passage 5. This return flow of the gases down around the outer boiler shell 2 substantially increases the total amount of heat transferred from the gases to the water, and thereby increases the overall efficiency of the unit.

As previously indicated, the nipples 8 and 9 provide steam connections for purposes to be described later. However, these nipples are not used to deliver the steam from the boiler to the discharge line. Instead steam is taken from the upper end of the annular chamber 14 through a superheating tube 25 which passes down through the flue 10 and is centrally positioned with respect to the water tubes 11, so that it is exposed to the hottest part of the flame, to thereby superheat the steam after its delivery from the space 14. At its lower end the superheating tube 25 passes out through a window 27 in the boiler walls (Figs. 1, 2 and 4). The outer ends of the superheating tubes 25 from the two boilers are connected by fittings 28 (Figs. 1 and 2) to a common horizontal header 29 which in turn connects to a vertical header 30 adapted to be connected at its upper end by a fitting 31 to a discharge steam line 32.

The boiler described is primarily intended for operation in a closed steam heating system, in which the condensate is returned through a separate line to the boiler. Such a condensate return line is indicated at 33 in Fig. 2, and is connected to a vertical header 34 which in turn is connected through a check valve 35 to a T-fitting 36, the latter communicating with a pair of condensate return lines 37 which are connected by fittings 38 to tubes 39, which extend through the outer shell 2 of the boiler, as indicated in Fig. 4; so that all condensate is returned to the lower ends of the helical water passages in the boiler unit.

The construction of the burner per se is not a part of the present invention, and will not be described in detail. The burner units are indicated at 40 in Fig. 2 and are supported from the individual boiler shells by means of brackets 41 (Fig. 3) formed on the boiler shell and cooperating brackets 42 on the burners. The brackets 41 and 42 are detachably connected together by bolts.

As shown to best advantage in Fig. 3, the boiler shells 1 and 2 are secured at their lower edges to an annular frame member 45, the shells being provided with an outwardly extending flange 46 adapted to be bolted to the annular frame 45. The outer casings 15 are similarly provided with outwardly extending flanges 47 adapted to be bolted to the annular frame 45. The latter in turn is supported by suitable standards 48 which may extend to any supporting base.

If at any time repairs are required on the boiler, the assembly of the shells 1 and 2 can be removed by first removing the cover casing 15, together with the various gadgets (to be described later) supported thereon. Thereafter the boiler unit consisting of the shells 1 and 2 can be removed from the annular base 45.

The upper end wall 7 (Fig. 4) is preferably provided with radial corrugations to stiffen it and reduce its tendency to bulge upwardly in response to steam pressure.

30 The construction of the boiler units proper and the flues having been fully described, the control fittings and safety features will now be described with particular reference to Figs. 1 and 2.

35 Briefly, the boilers are heated by flames from the burners 40, which are adapted to use some volatile liquid fuel, such as gasoline. This fuel is supplied under pressure from any suitable source through a supply line 50. This supply line 50 delivers the fuel through an automatic regulating valve 51 to a line 52. Line 52 delivers the fuel through a solenoid valve 53 to a line 54 which connects through a T-fitting 55 with lines 56 going to the two burners 40.

40 45 To enable the boiler to be started from a distance, electrical ignition is provided; there being a pair of spark plugs 57 mounted on each burner and connected by high tension leads 58 and insulating bushings 59 to an energizing line extending through an electrical conduit system 60.

50 The regulating valve 51 is controlled by the steam pressure in the boilers, and the solenoid valve 53 is under the combined control of thermostatic means responsive to the flames of the burners 40 and a pressure switch 62.

55 When the solenoid valve is energized, it is in open condition to permit fuel to flow from line 52 to line 54, but closes whenever the solenoid is de-energized.

60 Referring to Fig. 9, the winding 53a of the solenoid valve 53 is connected in series with the contacts 62a of the pressure switch 62 and with the contacts 65a of a relay 65, to a source of current 66. The contacts 62a are normally closed, but open in response to excess steam pressure. The contacts 65a are also normally closed, but open in response to energization of relay 65, which is normally de-energized when the boiler is in operation. The operating circuit of relay 65 includes the source 66 and the contacts of a pair of sensitive relays 67 and 68, respectively. The windings of relays 67 and 68 are connected to thermocouples 69 and 70, respectively, which are positioned immediately above the burners 40-40, respectively. So long as the burners are in oper-

ation, current is generated in the thermocouples 69 and 70 to energize the relays 67 and 68 and hold their contacts open so that the relay 65 is de-energized and its contacts 65a are closed. However, should the flame of either of the burners 40—40 be extinguished for any reason, the associated relay 67 or 68 is quickly de-energized to close its contacts and energize the relay 65 which thereupon opens its contacts 65a to de-energize the winding 53a of the solenoid valve 53, 10 and shut off the fuel supply to the burners.

It will be apparent that winding 53a will also be de-energized should the steam pressure rise sufficiently to open contacts 52a of the pressure valve 62.

Likewise, should the current supply from the source 66 fail for any reason, the valve will be closed to shut off the fuel supply.

A manual switch 150 is shunted across the contacts 65a to complete the circuit to the solenoid winding 53a at the time of starting. This is necessary because when the thermocouples 68 and 70 are cold the relays 67 and 68 are de-energized to close their contacts and complete an energizing circuit to the relay 65 so that its contacts 65a are open.

It will be observed from Fig. 2 that the upper end of the steam connection 108 on the right boiler unit is connected by a pipe 115 to a T-connection 116 on the left boiler unit. This is for the purpose of interconnecting the upper portions of the two boiler units. The lower portions of the two boiler units are likewise interconnected by a pipe 117. These two cross connections, including the pipe 115 and the pipe 117, maintain the same water level in both boiler units. These cross connections also equalize the pressures at the upper and lower ends of the two boiler units, and prevent pressure surges through the water gauge glass. A water gauge 120 is 40 connected between the fitting 116 and a fitting 121, which connects the pipe 117 into the lower part of the left boiler unit.

It is desirable, in some instances, to provide forced draft in the unit to insure against a reversal of the draft due to external air currents or changes in air pressure. To this end, a fan 130 may be positioned within the common flue between the two boiler units, this fan being mounted on the upper end of a vertical shaft

which extends down through the bottom wall of the flue and into an electric motor 131 positioned therebelow. This electric motor is preferably energized from the same source of energy 66 (Fig. 9) as is employed to energize the solenoid valve winding 53a, so that in case of failure of the power supplied to the fan, the flame will be extinguished.

Although for the purpose of explaining the invention a specific embodiment thereof has been described in substantial detail, it is to be understood that various changes may be made in the particular construction shown without departing from the invention, which is to be limited only to the extent set forth in the appended claims.

15 I claim:

1. A boiler of the type described, comprising: a vertical, tubular inner boiler wall defining a passage for heating gases, a tubular outer boiler wall surrounding said inner wall and connected thereto at the top and bottom whereby the two walls together define an annular water chamber, a water tube positioned within said passage and connected at its opposite ends to the lower and upper ends, respectively, of said annular water chamber, said inner wall having a flat-topped helical corrugation extending outwardly therefrom into contact with said outer wall, and welded thereto at intervals to prevent collapse of said inner wall under steam pressure, said corrugations having vertical grooves extending therethrough at intervals to provide vertical paths for water circulation.

2. A boiler of the type described, comprising: a vertical, tubular inner boiler wall defining a passage for heating gases, a tubular outer boiler wall surrounding said inner wall and connected thereto at the top and bottom whereby the two walls together define an annular water chamber, a water tube positioned within said passage and connected at its opposite ends to the lower and upper ends, respectively, of said annular water chamber, said inner wall having a helical corrugation extending outwardly therefrom into contact with said outer wall, and welded thereto at intervals to prevent collapse of said inner wall under steam pressure, said corrugations having vertical grooves extending therethrough at intervals to provide vertical paths for water circulation.

JOSEPH P. SEAMONS.
